TEST TUBE RACK

Erik W. Anthon, Kensington, Calif., assignor to Warner-Lambert Pharmaceutical Company, Morris Plains, N.J., a corporation of Delaware

Continuation-in-part of design application Ser. No. 5,009, Dec. 12, 1966. This application Oct. 2, 1967, Ser. No. 8,937

Term of patent 14 years

(Cl. D16—1)

FIG. 1 is a front perspective view of the test tube rack embodying my design; and

FIG. 2 is a rear perspective view thereof.

This application is a continuation-in-part of my design application Ser. No. D. 5,009 filed Dec. 12, 1966 and now abandoned.

I claim:

The ornamental design for a test tube rack, as shown.
